UNITED STATES PATENT OFFICE.

JACQUES ROUSSO, OF LOS ANGELES, CALIFORNIA.

TOWEL-CABINET.

1,338,097.

Specification of Letters Patent. Patented Apr. 27, 1920.

Application filed July 29, 1918. Serial No. 247,230.

To all whom it may concern:

Be it known that I, JACQUES ROUSSO, a citizen of the United States, and a resident of the city of Los Angeles, county of Los Angeles, and State of California, have invented certain new and useful Improvements in Towel-Cabinets, of which the following is a specification.

My invention relates to improvements in 10 towel cabinets, and has for its object the provision of an improved construction of this character arranged to prevent the surreptitious or unauthorized removal of towels, while permitting of free use thereof.

15 Other objects will appear hereinafter.

The invention consists in the combinations and arrangements of parts hereinafter described and claimed.

20 The invention will be best understood by reference to the accompanying drawings forming a part of this specification, and in which,

25 Figure 1 is a vertical transverse section of a cabinet embodying the invention, and Fig. 2, a front face view thereof.

The preferred form of construction, as 30 illustrated in the drawings, comprises a suitable cabinet 5 adapted to be hung upon the wall, and provided with an outwardly swinging door 6. The cabinet is provided with a bottom 7 consisting of an upwardly and outwardly inclined shelf, and is divided by an upper shelf 8 into an upper clean towel compartment 9 and a lower soiled 35 towel compartment 10. A towel retaining rod 11 is arranged substantially horizontally in the upper portion of the compartment 9, being detachably secured at its inner end to the rear wall thereof. The towels 40 are provided with the usual gromets 14, adapted to be strung upon the rod 11 and slide or travel along the chain 12 during use. The towels are folded with their lower edges folded upwardly and outwardly, 45 as indicated, and are strung or threaded upon the rod 11 depending therefrom with their lower edges resting upon and supported by shelf 8, thus relieving the rod 11 of substantially all the weight or strain 50 from the towels and permitting of the use of a large number of towels without unduly straining the rod 11 and its attachment with the cabinet. In order to retain the clean towels in position on rod 11 and shelf 8, binding chains 16 are arranged as indicated, 55 to yieldingly embrace the bundle of towels

suspended on rod 11. These chains are secured at their upper inner ends to the upper rear wall of compartment 9 on opposite sides of rod 11, and are extended outwardly 60 around the edges of the bundle of towels, then inwardly over guide pulleys 17 and downwardly through slots 18 in the bottom 7 of the cabinet, weights 19 being secured to the lower ends of said chains. Slots 20 65 are provided in shelf 8 to permit of the free inward and outward movements of chains 16. By this arrangement, the bundle of towels will be nicely held in compact form on rod 11 and shelf 8, but may be readily 70 withdrawn from behind said chains, said chains automatically following up the bundle as it decreases in size, due to the tension exerted by weights 19. In this way, the bundle of towels is always maintained in 75 compact and orderly form, notwithstanding careless or rough usage.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such 85 variations and modifications as come within the scope of the appended claims.

Having described my invention, what I claim as new and desire to secure by Letters Patent is:—

1. A towel cabinet comprising a support; an upper supporting shelf secured to said support substantially midway of the height thereof; a lower supporting shelf arranged below said upper shelf and inclined upwardly and outwardly from said support; a horizontally disposed rod having its inner end detachably secured to said support above said upper shelf; a flexible chain secured at one end to the outer end of said rod and detachably secured at its other end to said support just above said lower shelf; binding chains secured to said support above and on opposite sides of said rod and adapted to embrace towels suspended thereon, said chains being passed around said towels and thence rearwardly of said support and depending therefrom, said upper shelf being slotted to permit rearward and forward movements of said binding chains and said lower supporting shelf being slotted to permit of the free passage of

said chains; guide pulleys located on said support and adapted to guide said binding chains; and weights on the lower ends of said binding chains, substantially as described.

2. A towel cabinet comprising a support; a horizontally rod having its inner end detachably secured to said support; a flexible guide element secured to the outer end of said rod and depending therefrom; a towel support positioned under said rod a distance less than the length of a towel and adapted to support the lower edges of upwardly folded towels depending therefrom; binding chains secured to said support above and on opposite sides of said rod, and adapted to embrace upwardly folded towels suspended thereon, said chains being passed around said towels and thence rearwardly and downwardly; guide pulleys located on said support and adapted to guide said binding chains; and weights on the lower ends of said binding chains, substantially as described.

25 3. A towel cabinet comprising a support; a horizontally disposed rod having its inner end detachably secured to said support; a guide element secured to the outer end of said rod; and yieldable binding elements connected with said support above and on

opposite sides of said rod, arranged and adapted to be extended thence outwardly over the top of a bundle of towels suspended on said rod, thence downwardly over the outer side of said bundle and thence inwardly to said support, substantially as described. 35

4. A towel cabinet comprising a support; a horizontally disposed rod having its inner end detachably secured to said support; a flexible guide element secured to the outer end of said rod and depending therefrom; flexible binding elements secured to said support above and on opposite sides of said rod, and adapted to embrace towels suspended 45 thereon, said binding elements being passed around said towels and thence rearwardly and downwardly; guide pulleys located on said support and adapted to guide said binding element; and weights on the lower ends 50 of said binding elements, substantially as described.

In testimony whereof I have signed my name to this specification in the presence of two subscribing witnesses.

JACQUES ROUSSO.
